U.S. Cl. D23—162

FIG. 1

FIG. 4

FIG. 1 is a perspective view of a blower showing my new design;

FIG. 2 is an enlarged side elevational view thereof, the opposite side being identical;

FIG. 3 is an enlarged fragmentary front elevational view, it being understood that the front is symmetrical in plane; and

FIG. 4 is an enlarged rear elevational view thereof.

The mesh is partially shown in FIGS. 1 and 4 for purposes of description, it being understood that the mesh is continuous over the area indicated. The blower is fragmentarily shown in FIG. 3 for convenience of illustration.

I claim:

The ornamental design for a blower, as shown and described.
